UNITED STATES PATENT OFFICE.

PHILIP M. WOLSIEFFER, OF CHICAGO, ILLINOIS.

STOCK-BOOK.

SPECIFICATION forming part of Letters Patent No. 577,998, dated March 2, 1897.

Application filed November 28, 1896. Serial No. 613,788. (No model.)

To all whom it may concern:

Be it known that I, PHILIP M. WOLSIEFFER, a citizen of the United States, residing at Chicago, in the county of Cook and State of Illinois, have invented certain new and useful Improvements in Stock-Books for Containing Postage-Stamps, Cards, &c., of which the following is a full, clear, and exact description.

10 My invention relates to improvements in that class of blank books which are used by dealers and collectors in postage and other stamps for containing their collections, and has for its object to provide a cheap, durable, 15 and efficient means for exhibiting the stock to customers without injuring the stamps by sticking them to the pages of a book by means of adhesive hinges or subjecting them to the mutilation of being creased and 20 bent in turning the leaves of the book.

A further object is to provide a suitable means by which stamps may be transmitted through the mails or carried in the pocket without subjecting them to the dangers of 25 being lost, mutilated or stuck together, and the protection being so light as to reduce postage to a minimum.

My invention consists of a stock-book containing any desired number of leaves folded 30 as hereinafter described and of the most convenient size, each leaf containing a series of parallel pockets for the reception of stamps and bound so that the pockets fall on the left-hand pages when the book is open.

35 In the accompanying drawings, in which similar letters of reference indicate corresponding parts, Figure 1 is a perspective view of my left-page stock-book opened to show the arrangement of the pocket-bearing 40 leaves for the reception of the stamps. Fig. 2 is a perspective view of a leaf cut ready to be formed into pockets. Fig. 3 is a perspective of the leaf folded, showing the arrangement of the pockets for the reception of the 45 stamps; and Fig. 4 is a longitudinal section of the leaf on the line xx .

A represents a sheet of paper cut at one side to form a series of strips B, which are provided with adhesive lower edges b . The 50 leaf is folded at a^2 , so that the strips B lie flatly upon the body sheet A, being securely fastened by their adhesive lower edges and

forming a series of horizontal parallel pockets. The flap a' is also provided with an adhesive inner surface and serves to strengthen 55 the pockets at the inner side of the leaf and to provide a protecting binding edge. After the strips B and the end flaps a' are firmly fastened in position the adhesive flap a is folded at a^3 to overlap all of the strips B, securing the pockets on the outer edge and providing a protecting edge to the leaf. A leaf is thus formed consisting of a series of 60 pockets, as shown in Fig. 3, for the reception of stamps, thus affording a convenient means 65 for the temporary arrangement of a collection, for the reception of duplicates, or for the exhibition of the dealer's stock, and protecting the stamps against the injuries of adhesive contact and crushing, whether arranged for exhibition series or for transmission through the mails.

By referring to Fig. 1 it will be seen that these leaves are bound into a book with the pockets on the left-hand pages of the book. 75 The advantage of this arrangement over the ordinary method of utilizing the right-hand page is obvious, for in books containing blocks or strips of stamps secured by one end only to the right-hand page the loose 80 ends of the stamps flare away from the leaf and strike the adjoining leaf before the one to which they are affixed is laid flatly upon it, crushing and ruining the stamps. In my stock-book such injuries are reduced to a 85 minimum, for stamps affixed to the left-hand page will lie closely against it and be supported by it when turned in the ordinary way from right to left. These pocket-bearing leaves are preferably bound into books, 90 as specified, but they may be made of any convenient size for carrying stamps in the pocket or used singly for their transmission through the mails.

Having thus described my invention, what 95 I claim, and desire to secure by Letters Patent, is—

1. A stock-book consisting of a series of leaves each leaf being made of a single sheet of paper comprising a body portion, A, and 100 a series of strips, B, which are provided with adhesive lower edges, and which are folded and gummed flatly upon the body portion, forming a series of pockets, the leaves being

bound so that their pocket-bearing sides fall upon the left side when the book is opened, substantially as shown and described.

2. A stock-book, consisting of a series of 5 pocket-bearing leaves, bound so that the pockets fall upon the left side when the book is opened, the leaf consisting of a single sheet of paper cut to form a body portion, A, and a series of horizontal strips, B, the latter being provided with adhesive lower

edges folded and flatly gummed upon the body portion, and forming a series of pockets which are supported at the binding edge by the protecting-strip a' and by the fold a , at the outer edge, substantially as shown and 15 described.

PHILIP M. WOLSIEFFER.
